(54) **VIOLIN, TEACHING THE ART OF**

(76) Inventor: **Robert Jr. McCormick**

Peter, Mr. Cormick, Roanoke Co. Virginia

Selmer Paul

The Schedule referred to in these Letters Patent are making part of the same containing a description to the words of the said Patent of McCormick's Inquiry of his improvement in teaching the art of performing on the Virtuoso.

Be it known that Robert Mc Cormick Jr of the County of Augusta in the State of Virginia have invented a new and useful improvement in teaching the art of performing on the Violin. His invention consists of the following parts viz. Scale No 1 sharp, Scale No 2 flat, Scale No 3 sharp and the tuning block. These several scales constructed as follows exhibit the notes, and are used in the following manner. The small bridge of a common Violin near the neck being taken away. Scale No 1 is inserted into the finger board by a slot or opening corresponding in shape to the scale. Another small bridge is placed instead of the common one about five eighths of an inch upon or within the finger board which raises it enough all the notes about that distance higher on the finger board. The scales are about four inches long and one of the same size, except the tuning block which only goes with the second or Δ strings.

The two scales are divided into parts, forming inclined projection rising at each semi-tone a foot above the part of an inch. Between the two scales stand the characters ♭ ♮ or in musical the four 1st law as they occur in the different keys in the Gothic scale & the sharp, as calculated after Dr. C. Regedorff D. major but will also answer for ^{the 1st} key of C. Major by moving them a fifth below. The notes in the scale stand thus.

Ch. 1

The characters on the musical scale, marked No. 2, stand thus.

No. 3.

The characters on the scale marked No. 3, are calculated for pieces typed on C major and stand thus.

Tuning scale - a side view.

The tuning scale or tuning block is a small piece of wood adapted to the above side with a projection, designating D & E with notches to it to receive the strings. Explanation of the foregoing scales A A Shows one of the finger board, a. a. the dotted line represents the ^{fourth} or ^{four and} bridge, b. b. about the ^{four and} fourths of the finger board extending above the foot or bridge, c. c. The movable scales containing the characters are two. One arranged to suit the different keys which may be made of wood a. The suitable material having chocolate fresh projections; at each tone, one dot between of the finger board above the scale, c, c, c, c, c, c, etc. dotted foot in which the string is confined to be pressed by the fingers on the note volume. The preceding scales each contain 17 degrees of sound, a little more than the octave or regular division of eight notes. In each octave the characters pass for two even times. The first time they occur above the key note in the lower octave they are unmarked; the second time they are marked with a dot smaller than the first, so they belong to the lower octave and are immediately below the principal key note. They occur also in the upper key or octave and are dotted above to show that they are above the principal key note and belong to the upper octave. The key note on each scale is marked with a bar-line; i.e. in the division of the strings. When the occasional flat sharp or natural occurs its place will be shown on the scale.

The letters which are represented as sharp or the beginning of a time, have the notes placed on them and their place supplied by natural signs.

Mode of operation Placing the Violin. The Violin is tuned by the tuning slide which is placed into the Nutcase till the notch $\mathfrak{B}$ comes under the Second or A string. The bridge or E string is raised to any height that may be desired, the Second or A string is then placed in the notch at $\mathfrak{B}$ and it unites here it produces the same sound with the bridge. The tuning slide is then shored back in order to let the Second string vibrate by the slide of $\mathfrak{A}$. The Third or D string is then placed in the notch $\mathfrak{A}$ and drawn in unison with the Second. The tuning slide or block is shored in the notch placed in the bridge $\mathfrak{B}$ as before which will advise the third string to vibrate between $\mathfrak{A}$ and $\mathfrak{D}$ the low string is placed in the notch $\mathfrak{D}$ and managed in like manner. This being done the tuning slide or block is removed.

Manner of playing by these scales The scale is shored into the Nutcase which is cut out of the finger board. The fingers are placed firmly on the holes between the frets or projections as they stand on the scale which confines the strings on these projecting frets from which it vibrates consequently the line will not bend back through the fingers. Should one upon draw a short distance, or the characters may be placed as in the preceding drawings in a book or otherwise and committed to memory by the learner, or they may be marked on paper and placed on the finger board of the Violin; or the characters may be cut on the finger board of the violin. The first hunter. Consider the best scale which is to have all these movable scales all of the size adopted to a Nutcase which is cut out of the finger board to receive them with elevated frets or blocks some time which have already been described.

What I claim as my invention and for which I desire a Patent are the 3 Music scales C, A, G, E, and their construction by them with the tuning slide or tuning block and the manner of applying the same to common Violins.
